UNITED STATES PATENT OFFICE.

NATHANIEL L. FOSTER, OF NEW ROCHELLE, NEW YORK.

FLY-PAPER.

1,080,892.

Specification of Letters Patent. Patented Dec. 9, 1913.

Application filed March 30, 1909. Serial No. 436,698.

To all whom it may concern:

Be it known that I, NATHANIEL L. FOSTER, a citizen of the United States, residing at New Rochelle, in the county of Westchester 5 and State of New York, have invented certain new and useful Improvements in Fly-Paper, of which the following is a specification.

My invention relates to fly paper, and 10 more particularly to that variety of such paper that is put on the market in the form of sheets, one side of which is coated with an adhesive substance. Such sheets are 15 adapted to be laid on tables or other supports in order that the flies may light upon, and become entangled in, the adhesive coating. It frequently happens, however, that articles are accidentally laid upon such 20 sheets or otherwise come in contact with the adhesive, and, since the material used for the coating is generally of an insoluble character, it is with great difficulty that articles which have once come into contact with the 25 adhesive can be cleaned. This has given rise to great inconvenience, and is one of the principal objections to the use of paper of this character. Another objection is that when, by careless handling, a sheet of paper 30 is accidentally dropped upon the table or floor, it usually falls face down and the adhesive becomes smeared over whatever the sheet happens to fall upon.

The primary object of the present invention, therefore, is to provide a sheet of fly 35 paper of this character having means which will prevent, or, at least, minimize, the possibility of the adhesive coating accidentally coming into contact with the floor, table or other articles.

40 A further object is to provide means by which such a sheet may be readily grasped and moved from place to place, without danger of the hands coming into contact with the adhesive.

45 With the above and other objects in view, my invention consists in the construction and arrangement hereinafter described, and illustrated in the accompanying drawing, in which—

50 Figure 1 is a perspective view of a sheet of my improved fly paper as it appears when in use; Fig. 2 is a perspective view of the back of a sheet as it appears when packed for shipment.

55 Referring to the drawings, 1 indicates a sheet of fly paper which may be of the usual

or any convenient size and material. On one side of the paper is spread a coating 2 of adhesive material, a margin 3, of clean paper being preserved around the edges of 60 such coating in the usual manner.

My improvement consists in the provision of a strip or band 4, secured at its ends to the middle of the opposite ends of the sheet. This strip is shorter than the length of the 65 sheet and, therefore, when applied thereto, serves to pull the sheet into a curved or cylindrical shape, causing the adhesive coating to form a concave surface. It will be observed that the strip 4 is held taut by the 70 weight and natural resiliency of the sheet, and extends across the sheet above and out of contact with the adhesive coating. This strip or band is preferably formed of paper, but it may consist of tape, cord or any other 75 suitable connection. It will be apparent, therefore, that the strip 4 serves as a guard to prevent objects from coming into contact with the upper surface of the paper and furthermore should a sheet be dropped accidentally the strip will maintain the coated 80 side of the paper concave and thus prevent it from coming into contact with the floor, even if it falls with its sticky side down. It is, of course, possible that small articles may be 85 laid or fall upon the sheet, but the guard strip 4 will be found a great help in preventing clothing and similar objects from coming into contact with the adhesive surface. Furthermore, it will be obvious that the 90 strip 4 constitutes a handle by means of which the paper may be moved from place to place without grasping the sheet itself.

While I have shown but a single strip, 4, 95 it will, of course, be understood that two or more such strips may be employed, if found desirable. In packing such sheets for shipment, it is the usual practice to place two sheets face to face as indicated at 1 and 1^a in Fig. 2, with their sticky surfaces 100 in contact. I, therefore, propose to arrange the strip 4, as shown in Fig. 2. By reference to this figure, it will be seen that the strip is permanently secured to the sheet at one end as at 4^a and that the strip is 105 then folded over flat upon the back of the sheet and its free end retained in position by means of a clip or strap 5, secured to the back of the sheet. The end 4^b of the strip is preferably provided with a glued surface, 110 or other means of attachment to the sheet may be employed. It will be noted that

this arrangement permits of the sheets being packed flat for shipment in the usual manner. When the user removes a pair of adhesive sheets from the box he slips the end 5 ^{4^b of the strip 4 out from under the retaining strap 5 and, after having separated the sheets, brings the strip up over the front of the sheet, and secures the end 4^b thereof to the opposite end of the sheet, as shown in 10 Fig. 1.}

It will thus be seen that I have provided a cheap, simple and practical means for largely obviating the objections heretofore inherent in sheet fly paper, and it is thought 15 that the numerous advantages of my invention will be readily appreciated by those skilled in the art.

What I claim is:—

1. The combination with a sheet of paper 20 having a coating of adhesive on one side thereof, of a flexible connection having one end attached to the uncoated side of such sheet adjacent each end thereof and, after

passing around the edges of such sheet, extending between the opposite ends thereof, ₂₅ such connection being slightly shorter than said sheet, whereby it serves to bend the same into the form of a segment of a cylinder.

2. The combination with a sheet of paper 30 having one side only coated with an adhesive, of a strip secured permanently at one end to one end of said sheet, and having a free end adapted to be secured to the other end of said sheet, said strip adapted to lie 35 flat on the uncoated side of said sheet to facilitate packing of the sheets for shipment, and means for retaining the strip in such position.

In testimony whereof I affix my signature, ₄₀ in presence of two witnesses.

NATHANIEL L. FOSTER.
